Primary Examiner — Alison M Ofstun*Assistant Examiner* — Evin F Ershock(74) Attorney, Agent, or Firm — Nixon & Vanderhye P.C.(57) CLAIM

The ornamental design for a brush with stand, as shown and described.

DESCRIPTION

FIG. 1 is a perspective view of a brush with stand showing my new ornamental design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines depict unclaimed portions of the article, and form no part of the claimed design.
